UNITED STATES PATENT OFFICE.

HENRY G. KAHL AND ADOLPH KEPPLER, OF NEW YORK, N. Y.

TOOL.

No. 926,496.

Specification of Letters Patent. Patented June 29, 1909.

Application filed March 19, 1908. Serial No. 422,159.

To all whom it may concern:

Be it known that we, HENRY G. KAHL, a citizen of the United States, and resident of the borough of Brooklyn, county of Kings, 5 city and State of New York, and ADOLPH KEPPLER, a citizen of the United States, and resident of Jamaica, Long Island, county of Queens, city and State of New York, have invented certain new and useful Improvements 10 in Tools, of which the following is a specification.

Our invention relates to tools and has for its object to combine a number of implements in one compact simple and easily operated 15 construction.

Our device will be fully described hereinafter and the features of novelty will be pointed out in the appended claims.

Reference is to be had to the accompanying drawings in which—

Figure 1 is an elevation of our improved tool in its closed condition, Fig. 2 is a similar view showing said tool in its open or spread condition and Fig. 3 is a plan view 25 thereof.

The tool comprises two members, A and B pivoted together at C and forming when the tool is closed as in Fig. 1 a handle.

D is an ax or hatchet blade formed integral with the member A and E is a hammer head forming part of the member B. The hammer head is provided with a claw 30 F for use in drawing nails.

G and G' are nipping jaws formed respectively on the members A and B and H, H' are cutting members also forming part respectively of the members A and B. The cutting members H and H' are intended for use as a wire cutting shears, or for any other 35 purpose for which they may be suitable. Each member A and B is provided with a number of oppositely disposed toothed or serrated concave jaws I, which form pipe wrenches of varying sizes. The members

40 A and B are further provided with oppositely disposed angular jaws or receivers J which together are intended for use as a nut wrench or as a key.

K is a punch forming part of or secured 45 to the member A and acting in conjunction with an aperture K' in the other member B. Each member A and B may also be provided with a number of tapered openings L of

various sizes, which may be used for drawing out wire. The member A has its free 55 end formed with claws M for use as a tack lifter and the free end of the member B is flattened for use as a screw-driver as indicated at N. The screw-driver N is so turned as to be in a plane at right angles to the 60 pivot C and the jaws M are located in a plane parallel with said pivot so that when the tool is in its closed condition as shown in Fig. 1, the said screw-driver will fit between the claws M of the tack lifter and lock 65 the free ends of the two members A and B together. This prevents wobbling of the two members A and B and provides a secure handle for the tool. It will be seen that in addition thereto, the two members A, B are 70 locked against lateral movement, at a point intermediate between their free ends and the pivot C, by the projection or punch K fitting into the aperture K'.

With our construction we therefore combine a large number of useful implements in one compact construction so that the individual members of the tool cannot be mislaid and are always ready for use.

By disposing the screw-driver as described 75 so the same is in a position to be easily used and also as before stated acts as a key or lock to lock the two members A and B against lateral movement relatively to each other when the tool is in its closed condition. 85

We claim:

1. In a combination tool, two members connected pivotally and one provided at its free end with a forked portion to receive the free end of the other member and prevent 90 lateral movement thereof, one of said members being provided, between its free end and the pivot, with a projection extending toward the other member, which has a recess to receive said projection and thus further 95 brace the two members against lateral movement.

2. In a combination tool, two members connected pivotally and one provided at its free end with a forked portion to receive 100 the free end of the other member and prevent lateral movement thereof, one of said members being provided, between its free end and the pivot, with a projection extending toward the other member, which has a 105 recess to receive said projection and thus

further brace the two members against lateral movement, the opposing faces of said members being provided with work-holding recesses, between the said projection and the 5 pivot, and also between the projection and the free ends of the members.

In testimony whereof we have set our

hands in the presence of two subscribing witnesses this 4th day of March 1908.

HENRY G. KAHL.
ADOLPH KEPPLER.
